United States Patent Office

Des. 211,439
Patented June 11, 1968

211,439

HANDBAG LOCK

David Damast, 22-14 40th Ave.,
Long Island City, N.Y. 11101

Filed Sept. 26, 1967, Ser. No. 8,739

Term of patent 3½ years

(Cl. D87—2)

I claim:

The ornamental design for a handbag lock, substantially as shown and described.
